US00D978593S

(12) **United States Design Patent** (10) **Patent No.:** **US D978,593 S**
(45) **Date of Patent:** **** Feb. 21, 2023**

(54) **DISPENSER**

(71) Applicant: **Brio Water Technology, Inc.**, City of Industry, CA (US)

(72) Inventor: **Arman Melkonian**, Granada Hills, CA (US)

(73) Assignee: **Brio Water Technology, Inc.**, City of Industry, CA (US)

(**) Term: **15 Years**

(21) Appl. No.: **29/739,376**

(22) Filed: **Jun. 24, 2020**

(51) LOC (14) Cl. **20-01**

(52) U.S. Cl.

USPC **D7/306**; D23/207

(58) **Field of Classification Search**

CLAIM

The ornamental design for a dispenser, as shown and described.

DESCRIPTION

FIG. 1 is a top perspective view, showing my new design; FIG. 2 is a bottom perspective view thereof; FIG. 3 is a front elevation view thereof; FIG. 4 is a rear elevation view thereof; FIG. 5 is a left side elevation view thereof; FIG. 6 is a right-side view thereof; FIG. 7 is a top plan view thereof; and, FIG. 8 is a bottom plan view thereof. The broken lines show portions of the dispenser that form no part of the claimed design.

1 Claim, 8 Drawing Sheets
